EDWIN P. WANNER, OF NEW YORK, N. Y.

DESIGN FOR A CHAIR BACK.

Application filed November 18, 1926. Serial No. 19,764. Term of patent 7 years.

To all whom it may concern:

Be it known that I, EDWIN P. WANNER, a citizen of the United States, and resident of the borough of Manhattan, city, county, and State of New York, have invented a new, original, and ornamental Design for a Chair Back, of which the following is a specification, reference being had to the accompanying drawing, forming part thereof.

Fig. 1 of the drawing shows a front view of a chair back embodying my new design;

Fig. 2 is a rear view of the chair back of Fig. 1, and Fig. 3 is a side view thereof.

The dominant feature of the design consists in the spindles of the chair back rounded on the back side thereof and flat on the front side, the flat front side of the spindle exposing the grain of the wood.

I claim:

The ornamental design for a chair back, substantially as herein shown and described.

EDWIN P. WANNER.
